FINGER RING AND METHOD OF MAKING IT

Jacob Karlan, New York, N. Y.

Application September 26, 1936; Serial No. 102,716

3 Claims. (Cl. 29—160.6)

My invention relates to a two-piece finger ring, in which the annulus is made from a blank, and the new feature is the formation of the side pieces for the crown of the ring from the blank of the annulus.

5 A further feature of my invention is the method of fabricating the ring annulus.

An object of the invention is to provide a stamped ring in which the annulus shaped from 10 a blank has, as an integral part thereof, box sides extending from the side of the blank of the annulus and side pieces raised from the body of the blank of the annulus in proximity of the box sides.

15 In the two-piece ring made hitherto, there is an annulus blank and a crown blank. The crown blank forms the top and the side pieces, whereas in my ring the side pieces and the box for the jewel top are formed from the blank for the 20 annulus.

25 By providing a ring having a top without side pieces, I permit a jeweler to have a selection of tops for different sizes of gems or stones to fit the same annulus. By forming the side pieces from the blank of the annulus, I reduce the amount of soldering since the only part to be soldered in my ring is the top, whereas in the two-piece ring hitherto made, the side pieces as well as the top which form the unit had to be 30 soldered to the annulus of the ring in the assembling.

35 Another advantage of my ring is that it permits the jeweler the selection of any desired top for the same annulus, without the necessity of using independent side pieces in conjunction with a top for a large size jewel or stone.

40 It may be remarked that in my ring, by forming the side pieces from the blank of the annulus, I in reality form the crown of the ring, with the exception of the top, from the blank of the annulus, thus providing a selectivity of decorations and jewels of various sizes with suitable tops for the annulus, without any change or additional labor on the annulus.

45 In the appended drawing forming part of this application,

Figure 1 is an elevation of a ring embodying my invention.

50 Figure 2 is a vertical section through the plane of the ring on the line 2—2, Figure 3, showing a slight modification of the ring.

55 Figure 3 is a top view of the ring in Figure 2, a portion of the top being removed to show the box formation of the ring to which the top is secured.

Figure 4 is a fragmentary plan of a stamped blank for the annulus.

Figure 5 is a section on line 5—5, Figure 4.

Figure 6 is a view similar to Figure 5 with the side pieces formed, and

Figure 7 is a fragmentary elevation of the blank, in which one of the wings is shown expanded, ready to be bent, while the other is shown bent at the sides only.

5 Referring to the drawing, 10 is the ring annulus formed of a blank 11. The blank is provided with side or lateral wings 12 at its central flattened part 13. To each side of the central part 13 in the body of the blank 11, thickened portions 14 are provided from which any desired 15 design may be formed by swedging, drawing or stamping.

20 As shown in Figure 4, the blank is stamped with a design suitable for the type of ring being made. The portion of the blank 11 at 14 is hollowed out on the inner surface which is to form the concave surface of the annulus (see Figures 2, 5 and 6), or it may be left solid as shown in Figure 1. After stamping the blank is trimmed of surplus metal.

25 As shown in Figures 2, 5 and 6, the thickened portions 14 have been drawn in forming the decoration thereon, thus providing a hollow 15 on the under or concave surface of the blank. This hollow is spanned transversely by the central part 30

13. This spanning portion of the blank provides lateral rigidity therat. Whether these portions 14 are drawn or swedged, they will present above the spanning central portion 13, spaced raised edges 22. These raised portions 14 constitute the 35 side pieces of the crown of the ring. Whether these side pieces are made solid, as shown in Figure 1, or hollow, as shown in Figure 2, they are then slotted parallel to the plane of the blank, to permit the severed portion or top 23 of side pieces 40 14 to move from the body of the blank when shaping the blank into an annulus. The slitting may be on straight lines or dented to give the desired configuration to the side walls of the side pieces 14 and to the annulus therat.

45 It is evident that the top 23 of each side piece 14 at the end remote from the central part 13 forms an integral part of the blank, although the top 23 is separated from the blank body as it 50 nears the central part 13, the separation or angular clearance therebetween increasing as they approach the central part 13 of the blank when it is shaped into an annulus.

The slitting accomplishes two functions: It permits giving the annulus of the ring a lateral 55

design on the side walls of the side pieces 14 and permits the slotted part to move relatively to the blank body when it is shaped into an annulus, in addition it gives the appearance of a heavier type of ring at the crown with a minimum of metal.

After the side pieces 14 have been raised from the body of the blank the wings 12 are shaped (see upper part of Figure 7) to form a central portion 17 and side portions 18. The side portions are then bent toward the central part 17 into the same direction as the side pieces 23 were raised from the blank (see the lower part of Figure 7), so that each section of the box formed 15 is of channelled cross-section, the channelled side of the box section being on the inside of the box, as best seen in Figure 3.

After the desired design has been formed in the wings and the blank, the wings are bent on 20 the junction line 19 of the wings with the blank to form the box sections or sides 20, as best seen in Figure 3.

It will be noted that the side portions 18 forming the channel of the box section, will approach 25 the edges of the raised side pieces 14, but there will be a clearance between them; see Figure 3.

To prevent the raised side pieces 14 from being bent accidentally toward the blank, I provide 30 prongs 21 on the side portions 18 of the wings, as best indicated in Figure 7, which prongs 21 will come under the adjacent edge of the side pieces 14 and form a support therefor. In cases where the side pieces 14 of the blank are brought to the level of the top of the formed box 20, they may 35 be soldered to the top when the top is soldered to the box, and thus omit the prongs 21.

It will be seen that in my construction the box is formed from two spaced channelled sections 40 formed integrally from lateral pieces or wings of the annulus blank, and that each of said channelled box portions has its depth of channel increasing as it rises from the blank, and although 45 said box sections extend toward the raised side pieces, they are not connected therewith except in forming a support so that the raised side pieces may not be depressed accidentally or otherwise.

The so-formed blank, when shaped into an annulus as indicated in Figures 1 to 3 inclusive, has a gap 24 which may be soldered when the 50 ring is finished. The top 25, to be fitted to the shaped box 20, is in conformity to said shape and

of a type common in ring findings for accommodating a jewel or a stone. As shown in the drawing, it is rectangular in configuration, provided with a central opening properly flared to accommodate a jewel or stone.

From the description, it will be seen that when the annulus is shaped, the only thing necessary to complete the ring is the top, so that in my ring formed of two pieces, the main piece formed of the annulus blank is provided with everything 10 except the gem or stone carrying top. Thus, I provide a ring in two parts which differs from the two-piece rings hitherto made, in that my top is without side pieces. The side pieces in my ring are raised from and integral with the blank from 15 which the annulus is formed, and so is the box which carries the top. The blank at the box bottom thereof and provides lateral rigidity for the annulus and box thereat.

I claim:

1. In a finger ring, an annulus formed from a blank having hollowed out spaced side pieces raised from the body of the blank and lateral box sections of channelled cross-section formed from 25 the body of the blank about the space of said side pieces, said blank having an integral portion thereof at the spaced side pieces extending between the box sections and lying in the inner annular area of the annulus, and a top secured to said box sections.

2. A method of making finger rings which comprises stamping a blank to present a central portion with side wings thereat and a raised body portion in the blank to each side of the central portion, slitting the raised portions of the blank in a plane parallel to the plane of the blank, shaping and bending the wings toward the raised portions to form a box thereat, and bending the blank into an annulus.

3. A method of making finger rings which comprises forming a blank presenting a central portion with side wings thereat and a raised body portion in the blank to each side of the central portion, slitting each raised portion of the blank parallel to the plane of the blank at the central part thereof, shaping and bending the wings into channelled sections and bending them toward the flattened central part to form a box, and bending the blank into an annulus.

JACOB KARLAN.
